UNITED STATES PATENT OFFICE

2,430,402

WORKMAN'S TIME RECORDER

Johan Albin Jonsson, Stockholm, Sweden, assignor to Telefonaktiebolaget L. M. Ericsson, Stockholm, Sweden, a company of Sweden

Application September 12, 1944, Serial No. 553,775
In Sweden September 2, 1943

4 Claims. (Cl. 234—43)

1

The invention relates to an arrangement in time recorders in which the commencement and conclusion of working time may be recorded on a card, in which a hole is punched for each recording.

The purpose of the invention is to provide an all-automatic apparatus of said kind which may be used during a longer period of time, for example one month, without any parts of the apparatus having to be manually adjusted. According to the invention this is obtained mainly by a time operated checking device, which moves the card-holder of the apparatus from its initial position one step laterally every twenty-four hours and after a certain number of such displacements releases the card-holder so that it returns to initial position, and in so doing changes the position of the stop limiting the insertion of the card in the holder.

The invention will be described more in detail with reference to annexed drawings. Fig. 1 is a side view partly in section of the parts of a time recorder embodying the invention. Fig. 2 is similar view, showing some of the details contained in Fig. 1 in another position and the locking device for the handle 151 omitted. Fig. 3 is a back view of the apparatus, the lever 127 being broken away and the handle 151 removed. Fig. 4 shows the opposed faces of a card and Fig. 5 illustrates corresponding faces of another card. Figs. 1-3 contain exclusively the details of the apparatus which are necessary for a clear understanding of the invention.

Should a card, which has not been punched previously, be inserted in the card-holder 1 of the apparatus, Fig. 1, its lower portion will act upon a two-legged stop-lever 11, fixed to a rotatable shaft 12. In a manner described in my U. S. patent application No. 553,774, filed September 12, 1944, which explains how a card is recorded and punched, the link 21, on account of the turning of the stop lever, will lift the pawl 23 so that the handle 27 of the apparatus is released and recording can follow, a hole thereby also being punched in the card. When the card is again inserted in the card-holder, it is stopped by a member for finding the holes (hole-finder), as will also be seen from the above-mentioned patent application, said finder thereby automatically being introduced in the hole, whereby a succeeding recording will be performed just below the preceding recording. Presuming that the card be punched the first day of a certain month, the first recording will take place in column 1, Fig. 4, opposite the uppermost "Arrived." The succeed-

2

ing recording takes place in the same column opposite "Leave." The next day, the second, the recording will be performed in column 2. This is achieved by the card-holder 1 automatically being moved laterally by a time-operated displacing device, the operation of which will be described hereinafter.

The card-holder 1, Fig. 3, is at the back provided with ears 111, 112, which encircle a screw 113, being supported in frame 114. The ear 111 to the left on the drawing is in the form of a nut. On the screw 113 rotating, the card-holder therefore will be displaced laterally. During the rotation of the screw a spring 115a in a spring-box 115 arranged in known manner at one end of the screw, is tensioned whereby the screw, on being released, automatically is restored to an initial position. At the other end of the screw is a gear pinion 116, which may be operated by a cog-wheel 117 fixed on a shaft 118. Said wheel 117, as is seen from the drawing, is not toothed round its entire periphery but has two diametrically opposed recesses, 141, 142. A ratchet wheel 119 is rigidly connected with the cog-wheel. The 20 ratchet wheel coacts with a step pawl 121 and a pawl 122. The step pawl is kept in operating position by a spring 123 and is turnable around a stud 124 mounted on a feeding lever 127. The pawl 122 is supported on a tap 126 and acted upon by a spring 125. The wheel 119 steps forward being actuated by said two-legged feeding lever 127 which is supported on shaft 118 and kept in the position shown in Fig. 1 by a spring 128. At its lower extremity the lever 127 is bent to form 25 an angle 131 which projects into a slot 132 in a plate 133 fixed on the frame of the apparatus. Said angular extremity 131 is acted upon, according to the proposed design, by a time-controlled mechanism so that the angular end 131 every 30 twenty-four hours (before a certain hour, for example 12 p. m.) is moved upwardly in the slot 32 until the step pawl 121 on the lever 127 is moved back and falls into the next tooth groove. After said displacement the angular end 131 is released 35 at 12 p. m. by the clock mechanism, thus permitting the lever 127 to withdraw to its initial position by means of spring 128, whereby the step-wheel 119 moves forward one step. The wheel 117 turns the screw 113 over the pinion 116 thereby 40 displacing the card-holder 1, Fig. 3, a distance corresponding to a column on the card.

Said displacement is repeated in the same way once every twenty-four hours, when the clock mechanism lifts the angular end 131 in the 45 slot 132. After a certain number of displace- 50

ments, for example after one week or 8 days, the cog-wheel 117 has turned sufficiently to present one of the recesses 141 or 142 to the pinion 116. Under the influence of spring 115 the screw 113 being released in said manner returns the card-holder 1 to normal position.

At this displacement of the card-holder 1 to its initial position a new stop position in the card-holder will be formed for card 10 instead of the stop lever 11. Said alteration of the stop position will now be more closely described. On one side of the cog-wheel 117 a cam disk 143, Figs. 1-3, is mounted. When the wheel turns during the feeding operations, a stud 144 is pressed by a lever 145 against said cam disk. The lever 145 is fixed to a shaft 146 which, under the influence of a coil-spring 156, Fig. 3, tends to turn counter-clockwise Figs. 1 and 2. On the same shaft 146 is another lever 147 which engages a stud 148 on a stop lever 101. Said lever 101 is supported on a shaft 102 which is fixed at one extremity of an angular link 103 which, at its other extremity, is mounted on the same shaft 102 as the stop arm 11. When the cog-wheel 117 and the cam-disk 143 have turned clockwise to the position shown in Fig. 1, the stud 144 upon further rotation of said cam-disk moves counter-clockwise to the left, the lever 147 thereby also turning counter-clockwise. The lever 101 moves about the shaft 102 from the position in Fig. 1 to the position shown in Fig. 2. When now the card 10, Fig. 2, is inserted in the card-holder 1, its lower edge will touch against the lever 101 which lies somewhat further up than lever 11. Lever 101 is now pressed somewhat downwardly, causing link 103 to revolve, whereby the shaft 102 is turned clockwise in the same way as it is turned when lever 11 is acted upon. Said lever 101 when turning with the shaft 102 imparts movement to the members 15, 18 and 21 and causes a release of 40 the handle 27. When the card is recorded, the recording will lie somewhat lower on the card than the recording as described previously in column 1. The latter recording is intended to be performed in column 9, Fig. 4, opposite the upper "Arrived" on the card. The columns 9-16 in Fig. 4 may be placed on the same card as columns 1-8, but at the opposite face of the card. The horizontal rows for "Arrived" and "Leave" in the columns 9-16 lie, as is seen from Fig. 4, at different distance from the lower edge of the card than corresponding rows in columns 1-8. A row in columns 9-16 then falls between two rows in columns 1-8. On account of said difference in spacing from the lower edge of the card a faulty recording of the card would be detected on checking. Thus, should a recording take place in column 2 instead of in column 10, recording will follow between two rows in column 2.

When columns 9-16 have been employed, the cog-wheel 117 has been displaced so far that the succeeding recess 141 or 142 arrives opposite the pinion 116, whereby the card-holder again is restored to initial position. Simultaneously, the stud 144, Fig. 2, is moved clockwise to the inner edge of cam-disk 143, causing the stop 101 to return to the position shown in Fig. 1.

In order to cause re-adjusting of the card-holder when needed, for example towards the 70

end of a month, the apparatus is provided with a special lever 151, Fig. 1, in the form of a handle, rotatable around the shaft 150. The lever 151 is in normal position moved by a spring 152 against a stop 155. Said handle projects from the casing 153, 154 of the apparatus. If the projecting portion of the handle is pushed down, the lever 127 moves counter-clockwise and the card-holder is displaced one step, as before described. The handle 151 thereby moves in a slot in casing 153. To prevent unauthorized interference, the handle 151 is locked as a rule. The handle passes through a hole 162 in a link 161, which is kept in the position shown in Fig. 1 by the right-hand extremity of the lever 163 which is pivotally mounted at its left end. The lever 163 is kept in the position shown by a stud 167 on a normally upturned lever 164. When the lever 164 has said position, the handle 151 cannot be operated. Should a locking device, 165, 166 however be acted upon by means of a fitting key, the lever 164 can be turned clockwise into the horizontal position as shown. In such a case the lever 163 can be lowered to the position indicated by a dotted line, thus enabling operation of the handle 151.

I claim:

1. In a time recorder, a holder for receiving a card, means for moving the card holder step-wise in one direction from an initial position, means for returning the card holder to initial position after a plurality of stepwise movements, a stop for limiting the introduction of the card into said holder, a stop member movable into a position in said holder for arresting the card in a position above the card stop, and a cam actuated by the card moving means for periodically moving said stop member into operative position.

2. A time recorder as claimed in claim 1 provided with a support common to the stop and the stop member.

3. A time recorder as claimed in claim 1 provided with means movably supporting the stop member in operative position whereby said member may be moved a limited distance under the influence of pressure exerted on the card engaged therewith.

4. A time recorder as claimed in claim 1 wherein in said holder moving means includes a rotatable feed member engaging and operating said card holder, a pinion on said feed member, a toothed wheel meshing with said pinion and having recesses in which the pinion may freely revolve while said holder is moved by said returning means, a step wheel on said toothed wheel, and a periodically actuated lever for operating said step wheel.
